(57) **CLAIM**

The ornamental design for combined chair and table, as shown and described.

DESCRIPTION

FIG. 1 is a front perspective view of the combined chair and table showing our new design;

FIG. 2 is a side elevational view,

FIG. 3 is a front elevational view,

FIG. 4 is a rear elevational view,

FIG. 5 is a top plan view; and,

FIG. 6 is a bottom plan view.

The fragmented cross-hatching is understood to represent fabric and would be continuous throughout the circumscribed area.

1 Claim, 6 Drawing Sheets
